HARRY BRIDGMAN SMITH, OF BROOKLYN, NEW YORK, ASSIGNOR TO LIGHTSHIP CLOTH BOARD CORPORATION, OF BROOKLYN, NEW YORK, A CORPORATION OF NEW YORK.

CLOTH BOARD AND SIMILAR ARTICLE.

Application filed October 18, 1923. Serial No. 669,388.

My invention relates to cloth boards and similar articles of a general character similar to those disclosed in a companion application (Case A) executed on even date here-
with.

The objects of the present invention are in general similar to those stated in said companion application, but it is a more particular object of the present invention to still further improve the cloth board structure disclosed in said companion application by so forming the materials and especially the filler materials employed, that, with the same weight of material a board may be produced which has much greater thickness, strength and stiffness, or a board of given dimensions and a certain amount of strength or rigidity may be produced with much less material than has heretofore been possible.

In its physical embodiment, as herein disclosed, the invention comprises a filler consisting of one or more strips or webs of suitable sheet fibrous material, adhesively secured together, and enclosed in an envelope of suitable sheet fibrous material much wider than the filler sheets or strips, and folded or adhesively secured to completely enclose and cover the broad sides and longitudinal edges of the filler, and otherwise embodying characteristics more fully explained in the above mentioned companion application, but with the important addition that the filler strip webs, or certain of them, are embossed or creased in a more or less transverse direction; and preferably these embossings are of a special character, such that the effective thickness of the corrugated web is materially increased, and its strength and stiffness is also very materially increased when properly incorporated in the cloth board structure, with a very small reduction in the length of filler material provided, and therefore with a given amount of material a very much thicker board, and one which is materially stiffer, stronger and lighter, may be produced, with great economy in the cost of material and also in shipping charges.

The characteristics and advantages of the invention are further sufficiently explained in connection with the following detail description of the accompanying drawings, which show certain exemplifying embodiments of the invention, and also explain sufficiently how the articles may be advanta-

geously produced. After considering these 55 embodiments, it will be understood that many variations may be made, and I contemplate the employment of any structures that are properly within the scope of the ap-
pended claims.

Figure 1 is a perspective view of a cloth board or similar article embodying the invention in one form, with layers of the component materials broken away in progressive fashion for explanatory purposes.

Figure 2 is a fragmentary end perspective of the same.

Figure 3 is a perspective view sufficiently explaining one suitable method of producing the articles of Figures 1 and 2.

Figure 4 is a perspective view of a modified structure.

Figure 5 sufficiently explains one suitable method of producing the structure of Figure 4.

As particularly exemplified in Figure 1, the cloth board is composed of various layers or pieces of suitable fibrous sheet material such as various grades of cardboard or other suitable paper stock, usually of substantial thickness. One important advantage of the invention is that it enables the cheapest available grades of material to be advantageously utilized, and therefore the article may be composed in large part, of 85 material of the kind known as strawboard.

The complete article comprises a filler F consisting of one or a suitable plurality of layers of suitable material such as strawboard or other suitable paper stock. Specifically, in this particular example, the filler consists of three layers of which two layers consist of embossed or ribbed sheets 1 and 3 and the other is an interposed plain layer consisting of a sheet 2, which may be of 95 similar material or may be of cardboard of higher grade than strawboard. The filler layers are adhesively secured together, and the complete filler is enclosed in an envelope consisting of a cover sheet C of suitable 100 fibrous sheet material wider than the filler sheets or strips, and usually more than twice as wide, folded and adhesively secured upon the filler as clearly indicated in Figure 1, in which the longitudinal edges 6 of the envelope are brought close together or in abutting relation, so that this surface as well as the opposite surface of the covered board is

entirely free and smooth from any projections or irregularities. The longitudinal edges 8 are also smoothly rounded or convexly formed to avoid sharp corners and a great variety of fabrics including very delicate and expensive fabrics may be wound upon the board without possibility of injury.

While the embossed layers 1 and 3 may vary greatly in character, and in a broader aspect of the invention ordinary corrugated cardboard or strawboard may be used for this purpose, it is preferable to produce the ribs or embossed formations in a particular manner and in a particular arrangement. In the present instance the creases or ribs 4 and 5 are of the character which I designate for convenience as "crimp creases" produced in the sheets or webs of material prior to assembly, these ribs being produced by applying cooperating crimping instrumentalities at opposite sides of the sheets and squeezing up a rib or bead on one side of the sheet and forming an opposite concavity or depression in the opposite side, the paper composing the bead being somewhat broken down in structure and having its component layers somewhat separated; and these operations are repeated to form a plurality of the parallel ribs, which may be in more or less widely spaced relation and not necessarily very close together. By producing the rib formations in this manner the effective length of the strip or web of raw material, is very little reduced or in other words, the effective thickness of the web is materially increased without very materially shortening it. Greater structural strength is obtained by arranging the ribs diagonally in respect to the length of their respective sheets 1 and 3, and preferably also, ribs on the different sheets are arranged in diagonal relation and at a substantial angle to each other.

When a plain sheet 2 is interposed between the embossed sheets adhesive may be applied all over both faces of the plain sheet, and the crests of the ribs 5 on sheet 3 will then adhesively adhere to one face of the plain sheet, and the broader surfaces between the ribs 4 of sheet 1 will adhere to the other surface of the plain sheet. Otherwise adhesive may be applied to the embossed sheets or to the crests of the ribs thereof.

Figure 3 sufficiently explains one suitable method of producing the cloth boards described, this being what I call a continuous production method in which the filler sheets 1, 2 and 3 are advanced in the form of continuous webs, the creases or ribs 4 and 5 are produced on certain of the webs such as 1 and 3, adhesive is applied to certain web surfaces such as those of web 2, the envelope sheet C is also advanced in the form of a continuous web, and adhesive is suitably applied

to it or to our surfaces of the core material to which the envelope is applied; the webs are then brought together and secured or folded over and adhesively secured, the longitudinal edges 8 are suitably pressed or otherwise treated to produce the smoothly rounded formation described, and the continuous assembly so produced is then severed transversely, usually at regular intervals, to produce the completed cloth boards B of suitable length for the purpose in view.

Figure 4 shows a modified construction in which two sheets or layers 1 and 3 of ribbed or embossed material are provided to form the core structure, without any interposed sheet of smooth or plain material. To adhesively secure the sheets 1 and 3 together, adhesive is applied to the crests of the ribs 4 or 5, or both which therefore adhere at every point of intersection.

Figure 5 illustrates a modified production method suitable for the articles of Figure 4, which will be sufficiently obvious from the preceding explanations, except that, in this instance, one edge margin 10 of the cover web is overlapped upon the other margin, producing a lapped joint. This is unobjectionable in certain cases, but when desired any irregularity due to the thickness of the overlapped margin 10 may be reduced or eliminated by suitable pressing, producing the formation shown in Figure 4, in which the underlying margin 12 is depressed sufficiently to eliminate any appreciable rib or projection on the surface of the completed board. Otherwise the meeting edges of the envelope may be skived or beveled to provide a smooth overlapping joint.

While continuous production methods as here briefly explained are preferred in many cases, the articles may, of course, be produced in other ways. Continuous production methods are not a part of the present invention but are described and claimed in a companion application executed on even date herewith.

What I claim is:

1. A cloth board or similar article, comprising a core sheet of fibrous material having ribs spaced substantially apart, and an envelope sheet of paper much wider than the core sheet, folded and adhesively secured to the broad faces of the core and enclosing the longitudinal core edges, and having smooth external surfaces and rounded longitudinal edges.

2. A cloth board or similar article, comprising a plurality of filler sheets, at least two of which have diagonal embossed and relatively widely spaced ribs, the ribs on different sheets running at an angle to each other, and an envelope of fibrous sheet material much wider than the filler structure and adhesively secured thereto and smooth-

ly covering the broad faces and longitudinal edges of the filler, the longitudinal envelope edges being convexly rounded.

3. A cloth board or the like, comprising
5 a plurality of sheets of fibrous filler material adhesively secured together; two of the filler sheets being provided with diagonal widely spaced embossed ribs, the ribs on the different sheets running at a substan-
10 tial angle to each other, an intermediate plain filler sheet, and an envelope consisting of a sheet of fibrous material of greater width than the filler sheets, adhesively secured to and smoothly covering the broad
15 faces and longitudinal edges of the filler, the longitudinal edges of the envelope being convexly rounded.
4. A cloth board or similar article, comprising an envelope consisting of a single
20 sheet of substantially smooth paper stock having broad smooth faces and rounded lon-

gitudinal edges, and enclosed therein a filler structure including a sheet of fibrous material having thereon a plurality of relatively widely spaced, parallel crimped creases, 25 which materially increase the thickness and strength of the filler sheet without considerable lengthwise contraction thereof.

5. A cloth board or like article comprising at least one filler sheet of fibrous material 30 of substantial thickness, said sheet being formed with ribs projecting at only one side of the sheet and relatively widely spaced apart, the relatively wide plane sheet areas between the ribs being longitudinally un- 35 interrupted, the filler being enclosed by an envelope of fibrous sheet material adhesively secured to the filler.

Signed at Brooklyn in the county of Kings and State of New York, this 5th day 40 of Oct., A. D. 1923.

HARRY BRIDGMAN SMITH.
